UNITED STATES PATENT OFFICE.

FRANCIS BRACKNEY, OF BALTIMORE, MARYLAND.

IMPROVEMENT IN STEAM-HEATER BOILERS.

Specification forming part of Letters Patent No. 123,767, dated February 20, 1872.

To all whom it may concern:

Be it known that I, FRANCIS BRACKNEY, of the city and county of Baltimore and State of Maryland, have invented certain Improvements in Low-Pressure Boilers for Steam-Heating, of which the following is a specification; and I do hereby declare that the same is a full, clear, and exact description of my said invention, reference being had to the accompanying drawing and to the letters of reference marked thereon.

In the following descriptive outline of my invention, it will be seen that it relates to a boiler for the purpose above named; consisting in, together with its other features, hereinafter enumerated, a number of cast-iron sections, each one entire, complete, and distinct in itself, the whole, however, of which, when fitted and joined together, only making up and composing the one sectional boiler. The different sections are connected by pipes, having threads cut upon them, which screw into the sections and hold them together. The fire-box or furnace is placed in the center of the boiler; and tubes running therefrom each way into smoke-chambers near the end of the boiler return thence into a flue, of circular or other shape, which runs completely through the boiler at its center, from front to back. The smoke-connection is made to the front or back of the boiler by means of a T-pipe, so placed that an opening is preserved through it and the center flue, with which it connects. A lifting door, *m*, on a hinge, covers the end of the T-connection, so attached with other mechanism as to be operated upon by the steam-pressure and to regulate the draught.

It will be seen that, as each section is a receptacle for water and a steam-generator independently of all others, the joints between the same are not exposed to the action of the fire; neither are there any joints at which leakage can possibly ensue, except at the connecting-pipes, the prevention of which at these points is merely a matter of ordinary workmanlike skill.

In the further description of my invention which follows, due reference must be had to the accompanying drawing, in which—

Figure 1 is a front elevation of my invention. Fig. 2 is a vertical longitudinal section of the same. Fig. 3 is a vertical transverse section through the fire-box on line W X. Fig. 4 is a vertical transverse section through line X Y.

Similar letters of reference indicate similar parts of my invention.

A A represent the center or furnace sections. A' A' are plain sections. A" A" are the smoke-chamber sections. Each section is entire in itself, and no steam-joints whatever are required, except at the point of attachment, *a*. The joints at *b* are only of such character as may be found necessary to render them smoke-tight. The pipes *G* have threads cut upon them at each end, the end *g* having a longer thread than at *g'*. The object of this difference in the length of the threads is to facilitate the work of connecting the sections. Were the threads not so arranged, when the faces *b b* are brought together as a joint, the pipes could not be inserted. As it is, the end *g*, upon which is a lock-nut, *g''*, now run back, is screwed into and through the section far enough to allow the end *g'* to enter the opposite hole in the other section. The pipe is then screwed into the latter section, a sufficient part of its length still remaining in the other, and the lock-nut *g''* brought to its proper place against the side of the section. If desired, tie-bolts *h* may be run through these pipes, extending through all the sections, to assist, if necessary, in the securing of the boiler-sections, or for other purposes. B B represent the lower series of tubes, which run from the furnace C to the smoke-chambers D D. E E are the upper or return tubes, extending into and between the smoke-chambers D D and the smoke-flue F. By the position of the furnace C in the center of the boiler, and the tubes running each way to the smoke-chambers, and returning thence into the smoke-flue, a double-radiating draught is caused. The smoke-chambers D D are formed within the sections A" A", and the smoke-flue F within those of A A, one-half being in each. The flue F extends entirely through the boiler from front to back, its cleaning out being thereby facilitated. The sections A A and A' A', next to them, are somewhat deeper than the others, that ample height under the grate-bars *e* may be had. Those parts, *H*, of the sections wherein the pipes *G* are inserted are set back from the faces *b*, at which the sections join, to allow for the insertion of the pipes. K K are cleaning-out flues, reaching into the smoke-chambers D D. To the center flue F I attach, at either the front or back of the boiler, a T

smoke-connection, L, and at the other side of the boiler a cap, M, over the opening. The draught-door is represented by m.

The feed of water can be maintained by any suitable means whereby all the sections may be equally supplied, and any ordinary method adopted for ascertaining the pressure therein.

The pressure will never be high, this apparatus being of a class known as "low-pressure heating-boilers."

It is obvious, from the foregoing description of my invention, that it is my object to produce a boiler having, together with a double-radiating draught, a greatly-increased heating-surface over others of its class; that in this sectional boiler I combine simplicity of attachment by pipes, through which there is a perfect circulation; and, also, that, as a natural result of its construction, in this boiler there are absolutely no joints at which steam or water leakages can ensue.

It will be furthermore seen that convenient means are adopted for the cleaning out of the smoke-tubes and flues.

Having thus described my invention, what I claim as new, and desire to secure by Letters Patent, is—

1. The combination of the center flue F, extending transversely completely through the boiler, with the double series of return-flues E E, when arranged substantially as and for the purposes herein specified.

2. In low-pressure steam-heating boilers, an improvement consisting in a furnace, C, placed midway of the front elevation, as shown in Figs. 1 and 2, and as used in connection with the double series of direct-acting flues B B, the double series of return-flues E E, and the center flue F, substantially as set forth.

3. A counter recess, formed by the setting back of the parts H in the adjoining faces of any two of the separate sections, substantially as set forth, for the purpose specified.

FRANCIS BRACKNEY.
